UNITED STATES PATENT OFFICE.

JAMES W. YOUNG, OF SNYDER, TEXAS, ASSIGNOR OF ONE-HALF TO GUY McGEE, OF SNYDER, TEXAS.

OIL-STOVE.

992,626.

Specification of Letters Patent.

Patented May 16, 1911.

Application filed February 10, 1910. Serial No. 543,091.

To all whom it may concern:

Be it known that I, JAMES W. YOUNG, a citizen of the United States, residing at Snyder, in the county of Scurry, State of Texas, have invented certain new and useful Improvements in Oil-Stoves; and I do hereby declare the following to be a full, clear, and exact description of the invention, such as will enable others skilled in the art to 19 which it appertains to make and use the same.

This invention relates to oil burners for cook stoves and its principal object is to provide an improved general construction 15 of burner which can be used in any of the ordinary types of cook stoves without requiring great changes to be made in the structure of the stove.

The invention consists in general of an 20 improved construction of burner of this description and further consists in certain novel details of construction and combinations of parts hereinafter fully described, illustrated in the accompanying drawings, 25 and specifically set forth in the claims.

In the accompanying drawings, like characters of reference indicate like parts in the several views, and:—Figure 1 is a side elevation of a stove partly in section 30 showing the burner parts in position. Fig. 2 is a section on the line 2—2 of Fig. 1. Fig. 3 is a section on the line 3—3 of Fig. 1. Fig. 4 is a detail view of the oil receiving pan. Fig. 5 is a detail bottom view of a 35 certain protector plate forming a portion of this invention.

The numeral 10 indicates the body of a stove and this stove body is provided in its rear wall with the usual flue opening 11 40 communicating with the stove pipe 12. The stove body is also equipped with the ordinary fire-box 13 wherein is located a grate 14. This fire-box is also provided with a draft opening covered by a door 15 which 45 may be opened or closed to regulate the draft. The fire-box 13 is provided with a bottom 16 wherein is a centrally disposed opening 17 which communicates with a chamber corresponding to the ash pit of the 50 ordinary stove and which chamber projects out in front of the fire-box as indicated at 18 and is provided with a top 19 which may be a forwardly extending continuation of the bottom 16 having a series of openings 55 20 formed therein for producing draft. In

this chamber is held an oil pan 21 of substantially triangular shape in plan and having its narrow end toward the front. Extending upward through the top 19 is a drip tube 22 wherein is a valve 23. On the 63 upper end of this drip tube is an oil receptacle 24 preferably in the form of a funnel.

Within the fire-box 13 is held a series of horizontally disposed superposed baffle plates 25 each provided with a multiplicity 65 of openings 26, the openings in each plate being in staggered relation to the openings in the plates next thereto. These plates 25 are held in position by means of brackets 27 each comprising a zig-zag strip of metal 70 with the portions of the zig-zag lying in parallel relation so that the metal forms engaging and spacing means for the plates.

At 28 is indicated the oven top and extending from the sides of the fire-box to the 75 flue opening 11 are flue sides 29 whereon rests a substantially triangular cover plate 30, thus forming a flue tapered from front to rear and leading from the fire-box to the flue opening in the body. This plate 30 is 80 preferably in spaced relation to the cast iron top of the stove so that direct impingement of the flame on the top is prevented.

In the operation of this device the receptacle 24 is filled with the preferred quality 85 of oil and the valve opened so that it drops slowly through the drip tube into the pan 21 where it may be lighted. The flame will be carried by the draft entering through the openings 20 up through the opening 17 90 and will pass through the multiplicity of openings in the different baffle plates and thence out by way of the triangular flue to the stove pipe 12. At first, by reason of the coldness of the plates 25, a certain amount 95 of soot will collect on these plates, but after the plates become heated by the flame this soot will be burned off and will serve to increase the heat passing through the flue and thus keep the stove as hot as may be desired.

There has thus been provided a simple and efficient device of the kind described and for the purpose specified.

Having thus described the invention, what 105 is claimed as new, is:—

1. In an oil stove, a body having a flue opening in the rear, a fire-box in the body having a bottom provided with an opening, a flue tapering from front to rear and lead- 110

ing from the fire-box to the flue opening in the rear, an oil pan below said fire-box and extending out in front of said body, a perforated cover on the outwardly extending portion of the oil-pan, a drip tube extending upwardly from the oil pan, a valve in said drip tube, an oil receptacle on the upper end of the drip tube, a series of superposed baffle plates 25 extending across said fire-box and each provided with a multiplicity of perforations, the perforations in each of said plates being in staggered relation to the perforations in the next adjacent plates, means to hold said baffle plates 30 in spaced relation in the fire-box.

10 2. In an oil stove, a body having a flue opening in the rear, a fire-box in the body having a bottom provided with an opening, an oil pan below said fire-box and extending 15 out in front of said body, a perforated cover on the outwardly extending portion of the

oil-pan, a drip tube extending upwardly from the oil pan, a valve in said drip tube, an oil receptacle on the upper end of the drip tube, a series of superposed baffle plates 25 extending across said fire-box and each provided with a multiplicity of perforations, the perforations in each of said plates being in staggered relation to the perforations in the next adjacent plates, means to hold said baffle plates 30 in spaced relation in the fire-box, and a flue tapered from front to rear and leading from the fire-box to the flue opening in the body, the top of said flue being in spaced relation to the top of the 35 stove body.

In testimony whereof, I affix my signature in presence of two witnesses.

JAMES W. YOUNG.
